UNITED STATES PATENT OFFICE.

DAVID H. NASH, OF CHURCH ROAD, VIRGINIA.

AIR-MIXER FOR GASOLENE-ENGINES.

1,265,484.

Specification of Letters Patent. Patented May 7, 1918.

Application filed January 23, 1917. Serial No. 143,991.

To all whom it may concern:

Be it known that I, DAVID H. NASH, a citizen of the United States, residing at Church Road, in the county of Dinwiddie and State 5 of Virginia, have invented certain new and useful Improvements in Air-Mixers for Gasolene-Engines; and I do hereby declare the following to be a full, clear, and exact description of the invention, such as will 10 enable others skilled in the art to which it appertains to make and use the same.

This invention relates to an air mixer for gasolene engines and has for one of its objects the provision of a device of this character, whereby air will be automatically fed 15 to the manifold of the engine as the speed thereof increases.

Another object of this invention is to provide a heat conducting pipe connected to 20 the manifold and adapted to receive heated air about the exhaust pipe of the engine and having means therein so connected to the engine, whereby as the speed of the engine increases, the heated air will be fed to the 25 manifold so as to give greater power and speed to the engine upon the same amount of fuel.

A further object of this invention is to provide a valve within the heat conducting 30 pipe and connected to a governor that is driven by the engine, whereby as the speed of the engine is increased, the valve will be opened admitting heated air to the manifold.

35 A still further object of this invention is the provision of an air mixer for gasolene engines of the above stated character, which shall be simple, durable and efficient, and which may be manufactured and sold at a 40 comparatively low cost.

With these and other objects in view as will become more apparent as the description proceeds, the invention consists of certain novel features of construction, combination and arrangement of parts as will be hereinafter more fully described and claimed.

For a complete understanding of my invention, reference will be had to the following 50 description and accompanying drawings, in which:

Figure 1 is a side elevation of an air mixer for gasolene engines constructed in accordance with my invention, illustrating 55 it applied to an internal combustion engine,

Fig. 2 is a top plan view of the same.

Fig. 3 is a fragmentary sectional view through the inlet manifold,

Fig. 4 is a side elevation of the air valve 60 controlling mechanism removed from the engine.

Referring in detail to the drawings, the numeral 1 indicates as an entirety, an internal combustion engine used principally 65 upon automobiles having the usual manifold 2, to which the carburetor 3 is connected. Mounted upon the forward end of the engine 1 is the usual fan 4 carried by the fan shaft 5 for cooling the engine. The 70 engine 1 is mounted upon the automobile in the usual manner and has my invention applied thereto.

The manifold 2 has oppositely disposed 75 openings 6 to receive one end of a heat conducting pipe 7 which has formed thereon a collar 8, which abuts the manifold 2 and has its ends internally screwthreaded to receive a threaded plug 9 which cooperates with the collar 8 in securing the pipe 7 into 80 the openings 6 of the manifold 2. The heat conducting pipe 7 is bent at right angles and extends upwardly and has its uppermost end flared as illustrated at 10 to partially receive the exhaust pipe 11 of the engine 1 and is slightly spaced therefrom to 85 permit air to pass into the flared end 10 about the exhaust pipe so as to become thoroughly heated. The pipe 7 is provided in its lowermost wall within the manifold 2 90 with a plurality of enlarged openings 12 which permit the heated air passing through the heat conducting pipe 7 to enter the manifold. As the heated air passes through the openings 12, it is directed downwardly 95 within the manifold 2 and becomes thoroughly mixed with the fuel from the carburetor 3 as it passes upwardly through the manifold into the cylinders of the engine. The pipe 7 is also provided with a plurality 100 of small perforations 13 for permitting the heated air to enter the manifold. A butterfly valve 14 is located within the pipe 7 adjacent the manifold 2 and has secured or connected thereto a rod 15 which extends 105 rearwardly through the dash 16 of the automobile whereby the pipe 7 may be opened and closed to control the flow of heated air through the pipe 7 into the manifold 2.

A bearing 17 has formed thereon legs 18 110 and 19. The leg 18 is secured to the bolt 20, which secures the valve covering plate 21

to the engine and the arm 19 is secured to the bolt 22 which aids with other bolts in securing the crank case 23 to the cylinders of the engine 1. A rod 24 is journaled in the bearing 17 and has connected to one end thereof a rod 25 which is in turn pivoted to an arm 26 of a butterfly valve 27 located within the pipe 7 adjacent the butterfly valve 14. A coil spring 28 is mounted upon the rod 24 between the bearing 17 and a collar 29 which is rigidly secured to the rod. A pair of ears 30 are formed upon the end of the rod 24 remote from the end, which is connected to the link 25 and has pivoted thereto governor arms 31, which are provided with the usual weights 32. The free ends of the arms are pivoted to a rod 34 which is journaled in a bearing 35. The bearing 35 has an arm 36 formed thereon, which is secured to a bolt 37 upon the breather pipe or oil filling pipe on the engine 1. Secured to the end of the shaft 34 is a pulley 38, which has thereon an endless belt 39 that surrounds a pulley 40 upon the fan shaft 5. The fan shaft 5 is driven by a belt 41 connected to the crank shaft of the engine. The spring 28 normally holds the rod 24 and governor in its normal position so as to have the valve 27 in a closed position, preventing the heated air from passing through the pipe 7 into the manifold 2. After the engine 1 reaches a certain speed and it increases its speed from this point, the governor expands in the usual manner drawing upon the shaft or rod 24 against the tension of the spring 28 opening the valve 27, permitting the heated air in the pipe 7 to pass into the manifold 2. The heated air is drawn through the pipe 7, when the valve 27 is opened, by the suction of the cylinders of the engine 1. As the heated air enters the manifold 2, it mixes with the fuel from the carburetor 3 prior to entering the cylinders, which will give the engine increased speed and power upon the same amount of fuel, and also make a smoother running engine. As the speed of the engine decreases, the shaft 24 returns to its normal position under the influence of the spring 28, closing the valve 27 cutting off the supply of the heated air from the pipe 7, thus giving the engine a richer mix-

ture of fuel when running at a lower rate of speed, which is essential to obtaining correct running and good results from the engine. 55

When not desiring to use the air mixer or to prevent the heated air from passing into the manifold 2 when the engine is running at a high rate of speed, the rod 15 may 60 be rotated so as to close the valve 14, thus preventing any air from entering the manifold through the pipe 7.

While I have shown and described the preferred embodiment of my invention, it 65 will be understood that certain minor changes in construction, combination and arrangement of parts may be made without departing from the spirit and scope of the invention as claimed. 70

What is claimed is:

The combination with an engine including a manifold and an exhaust pipe, of a hot air intake pipe having one end disposed through the manifold and its other end associated with the exhaust pipe to receive heated air, a cap closing the end of the air intake pipe that extends through the manifold, said air intake pipe having a plurality of apertures therein and disposed within 80 the manifold to permit the heated air in the air intake pipe to enter the manifold, a valve located in the air intake pipe, a supporting structure carried by the engine, brackets carried by the supporting structure, 85 a rod slidable in said brackets, an arm secured to said rod and pivoted to the valve, a governor swivelly connected to said rod, a shaft journaled to the supporting structure and secured to the governor, means rotating 90 said shaft by the engine, adjusting nuts threaded to one end of the rods, and a coil spring surrounding the rods and having one end disposed against one of the brackets and its other end secured between the adjusting 95 nuts for normally urging the rod forwardly to close the valve.

In testimony whereof I affix my signature in presence of two witnesses.

DAVID H. NASH.
